BOX-MAKING MACHINE

Application filed September 1, 1927. Serial No. 216,883.

This invention relates to a box making machine, and more particularly a machine of the duplex type, adapted to produce wood berry boxes of the ordinary type constructed of thin sheet lumber having inclined sides and a wooden hoop binding the upper edge, with said hoop secured in place by means of wire staples.

It is an object of this invention to provide a machine having a plurality of alternately operating box forming mechanisms adapted to permit wooden boxes to be formed out of overlapping thin sheets of wood and a wooden hoop formed by a thin strip of wood adapted to be wound around the upper margin of the side walls of a box to which the hoop is secured by wire staples.

It is also an object of this invention to provide a box making machine of a double acting type adapted to automatically form boxes and secure hoops thereto to reinforce the upper margins of the boxes.

It is a further object of this invention to provide a box making machine adapted to shape a box from overlapping strips of thin sheet material and then bind the walls of the partially formed box with a flexible hoop band adapted to be automatically secured in place by wire staples to produce the finished box.

It is furthermore an object of this invention to provide a box making machine having a reciprocating holder adapted to automatically coact with a former to produce the body portion of a box, said former adapted to be intermittently rotated to permit a flexible hoop band to be bound around the upper margins of the box body previous to the automatic operation of a stapling mechanism which is adapted to operate after the hoop band is in place to secure the hoop to the box body by means of wire staples to produce a finished box adapted to be removed from the machine and nested with previously formed boxes until ready for use.

It is an important object of this invention to provide a box making machine of a form adapted to be continuously operated to permit boxes to be formed in rapid succession by alternately operating forming mecha-

nisms operated in predetermined order to permit one of the forming mechanisms to produce a box while the other forming mechanism is being supplied with material to be shaped into a box body to be reinforced by the binding hoop stapled in place by automatically acting stapling mechanisms acting in predetermined relation with respect to the forming mechanisms and with respect to hoop band feeding means.

Other and further important objects of this invention will be apparent from the disclosures in the specification and the accompanying drawings.

This invention (in a preferred form) is illustrated in the drawings and hereinafter more fully described.

On the drawings:

Figure 1 is a side elevation of a box making machine embodying the principles of this invention.

Figure 2 is a front elevation of the machine.

Figure 3 is an enlarged fragmentary vertical view of the rear end of the machine taken on line III—III of Figure 1.

Figure 4 is an enlarged fragmentary horizontal sectional view taken on line IV—IV of Figure 1.

Figure 5 is a detail sectional view taken on line V—V of Figure 4.

Figure 6 is a detail sectional view taken on line VI—VI of Figure 4.

Figure 7 is an enlarged fragmentary detail view of the former rotating mechanisms taken on line VII—VII of Figure 1.

Figure 8 is a fragmentary horizontal sectional view taken on line VIII—VIII of Figure 7.

Figure 9 is an enlarged fragmentary detail section of a former taken on line IX—IX of Figure 2, with parts shown in elevation.

Figure 10 is a front elevation of one of the forming mechanisms taken on line X—X of Figure 9.

Figure 11 is a top elevation of the former shown in Figure 10.

Figure 12 is a detail section of the former taken on line XII—XII of Figure 9.

Figure 13 is a transverse detail section of

the former taken on line XIII—XIII of Figure 9.

Figure 14 is an enlarged fragmentary vertical sectional view of the machine taken on line XIV—XIV of Figure 2 showing parts in 5 elevation.

Figure 15 is a back view of one of the box holders taken on line XV—XV of Figure 14.

Figure 16 is a horizontal detail view taken 10 on line XVI—XVI of Figure 14.

Figure 17 is an enlarged longitudinal detail section of one of the box holders taken on line XVII—XVII of Figure 14.

Figure 18 is an enlarged fragmentary front 15 elevation of one side of the machine illustrating the stapling mechanisms and a former.

Figure 19 is a fragmentary horizontal view 20 of the former and the hoop strip feed mechanism taken on line XIX—XIX of Figure 18.

Figure 20 is a fragmentary detail section of 25 the hoop strip feed mechanism taken on line XX—XX of Figure 19.

Figure 21 is a fragmentary sectional view 30 of the hoop strip feed mechanism showing the operation of the hoop catch in dotted lines.

Figure 22 is an enlarged transverse section 35 of one of the box formers showing the first step in the feeding of the hoop strip to the former.

Figure 23 is a similar section showing the 40 former after a complete rotation thereof with the hoop strip looped around the former.

Figure 24 is a similar section of the former 45 showing the box sides positioned against the partially completed hoop.

Figure 25 is a similar section of the former 50 showing the hoop strip completely wound around the former and around the box sides with the hoop riveted to the box sides.

Figure 26 is a side elevation of a completed 55 box removed from the machine.

As shown on the drawings:

The reference numeral 1 indicates a base 60 plate or foundation having rigidly secured thereon an upright framework 2, the upper end of which terminates in an integral upwardly directed yoke 3. Rigidly mounted on the front plate of the framework 2 is a shelf or table 4 the outer end of which is supported by means of a standard or leg 5 mounted on the base plate 1.

A stub shaft 6 is journaled in a bearing 7 provided on the framework yoke 3 and said shaft has freely or loosely mounted thereon a driving pulley 8 around which a driving belt, driven from any suitable source of power 80 is engaged. Mounted on the shaft 6 to the inside of the pulley 8 is a driving clutch 9 adapted to be moved into coacting relation with the pulley 8 by means of a bell crank 10 pivotally supported at 11 on the framework 2 (Figure 1). Pivotally connected to the outer end of the longer arm of the bell crank 10 is the upper end of a connecting rod 12 or bar 12 the lower end of which is pivotally

connected to the shorter end of an operating lever 13 which is fulcrumed on a pin 14 mounted on the lower portion of one side of the framework 2. The operating lever 13 is normally held in an elevated position by 70 means of a coil spring 15 attached to the framework 2. The operating lever projects through a guide slot 16 in the front plate of the framework 2 and has secured on the end thereof a foot pedal 17 to permit the machine to be started by an operator by merely pressing downwardly on the foot pedal 17 to cause the lever 13 to operate the bell crank 10 to throw the clutch 9 into operating engagement with the driving pulley 8 to cause a drive to 80 be transmitted to the shaft 6.

Mounted on the shaft 6 to the inside of the clutch 9 is a driving pinion 18 which is in mesh with a large gear 19. The gear 19 is supported on one projecting end of a main crank shaft 20 journaled in suitable bearings 21 formed on the framework yoke 3. Mounted on the main crank shaft 20 is an eccentric 22 to which an eccentric rod 23 is secured to be reciprocated with the rotation of the main crank shaft 20. Attached to the lower end of the eccentric rod 23 is the outer end of a crank arm 24 on which a pawl 25 is pivotally supported. The crank arm 24 is loosely mounted on a stub shaft 26 journaled in suitable bearings 27 provided on the machine framework 2. Seated on the shaft 26 adjacent the crank arm 24 is a timer gear ratchet 28 (Figure 6) with which a pawl 25 coacts to permit a drive to be transmitted from the main crank shaft 20 to the auxiliary shaft 26. Rigidly mounted on the framework 2 to the outside of the timer gear ratchet 28 is an inclined stop bar 29 for a purpose hereinafter more fully described.

Mounted on the rear face of the framework 2 is a bracket or casing 30 open at both sides, on the outer face of which four idler gears 31, 32, 33, and 34 are rotatably mounted in a vertical row in meshing relation with one another. The upper idler gear 31 is keyed on a stub shaft 35 which projects into the casing 30 and has an intermediate engaging gear 36 mounted on the inner end thereof in meshing or cooperating relation with an outer mutilated timer gear 37 which is loosely mounted on the shaft 26 adjacent the inner face of the casing 30. Projecting from the inner face of the mutilated timer gear 37 is a stud 38 on which is pivotally mounted a bell crank control member consisting of a hook arm 39 and a straight arm 40 which projects beyond the periphery of the mutilated gear. Secured at right angles to the outer projecting end of the bell crank arm 40 is a finger or rod 41 which projects inwardly past the plane of the stop arm 29 (Figure 4). The weight of the finger 41 and the long straight arm 40 of the bell crank member serves as a counter weight to hold 120

the hooked end 39 of the bell crank member in frictional engagement with the periphery of a toothed control cam 42 which is keyed on the shaft 26 to the inside of the mutilated timer gear 37. Also coacting with the periphery of the control cam 42 is a hooked arm 43 of a second bell crank member, having a straight arm 44. The bell crank member 43—44 is pivotally mounted on a stud 45 carried by an inner mutilated timer gear 46 which is loosely mounted on the shaft 26 between the control cam 42 and the framework 2, as clearly illustrated in Figures 1 and 4. Secured at right angles to the outer end of the bell crank arm 44 is an inwardly projecting finger or rod 47 which also projects through the plane of the stop bar 29. Mounted on the outer face of the mutilated gear 46 is a control spring 48 which engages the hooked arm 43 of the bell crank member 43—44 to resiliently hold the hooked arm 43 in frictional contact with the periphery of the control cam 42. Coacting with the periphery of the inner mutilated gear 46 is a lower intermediate gear 49 (Figure 5) which is keyed on a lower shaft 50 projecting through the casing 30 and also projecting forwardly through suitable bearings 51 from the machine framework 2. The lower idler gear 34 is mounted on the outer projecting end of the shaft 50. The forward end of the shaft 50 projects beneath the table 4 and is journaled in a bearing 52 supported on the standard 5. Keyed on the shaft 50 adjacent the inner side of the bearing 52 is a beveled gear 53 which is in mesh with a horizontal beveled gear 54. The beveled gear 54 is mounted on the lower end of a vertical shaft 55 mounted in a vertical sleeve 56a secured to the bottom of the table 4. The vertical shaft 55 has secured on the upper projecting end thereof a cross bar 56 for governing the operation of a pair of box holding mechanisms hereinafter more fully described.

As illustrated in Figure 16 the control cross bar 56 is provided with end longitudinal slots 57 through which pins 58 project to permit the bar to have sliding engagement with said pins when the bar is oscillated by the vertical shaft 55. Each end of the control cross bar 56 is adapted to operate a box holder mechanism when the machine is in operation. Each pin 58 is secured to a slide bar 59 which is positioned to slide between a pair of guide rails 60 mounted upon the upper face of the table 4. The top plate of each outer guide rail 60 has the outer projecting end thereof deflected downwardly to form an inclined runway 61 (Figure 14). Tracking on the runway or guide 61 is a roller 62 which is rotatably supported on a slide block 63 which is slidably mounted in a slotted portion of an upright or standard 64 which is rigidly mounted on the outer end of

the horizontal slide bar 59. Also pivotally attached to the slide block 63 is the lower end of a link or toggle bar 65, the upper end of which is pivotally connected to a crank arm 66. The other end of the crank arm 66 is secured to a horizontal stub shaft 67 which is journaled through the upper end of the standard 64 and has securely supported thereon a shank 68 on one end of which a holder 69 for the side walls and bottom of the box is positioned. The box holder 69 comprises a base plate and four side walls, the side walls being separated at the corners, and each of said side walls has the outer margin bent outwardly. The box holder shank 68 is provided with an axial passage in which a stem 70 is slidably disposed. The stem 70 slidably projects through the bottom of the holder 69 and has a box ejecting plate 71 secured thereto within the holder 69. Coiled springs 72 are mounted on the bottom of the ejecting plate 71 between said plate and the bottom of the holder 69 (Figure 17). Connected to a second crank arm 66 on the shaft 67 is the upper end of a coiled spring 74, the lower end of which is secured to the lower portion of the standard 64. The spring 74 acts to resiliently hold the guide roller 62 in rolling contact with the runway 61 and furthermore acts on the crank arm 66 to swing the holder 69 upwardly in an inclined loading position when the standard 64 is in its outermost position with the roller engaged on the depressed outer end of the guide rail 61. When a box holder is in an inclined position, as illustrated in Figure 14, it is positioned to permit convenient loading of the same by an operator who manually places a pair of transversely crossed box body strips at right angles to one another, with the middle portions 75 of said crossed strips superimposed so that the end portions of said strips may be bent to form the side walls 76 of a box which is to be formed.

The body blanks 75—76 from which a box is to be constructed are constructed of thin sheets of wood or other suitable material, and each blank is provided with a pair of transverse creases positioned at a distance apart sufficient to define the bottom of the base portion 75 of a box. When the body blanks are in position within the holder 69 the superimposed base portions 75 of a box are positioned to rest against the spring controlled ejecting plate 71 while the side walls 76 of the box project out of the holder 69 in a slightly inclined position permitted by the inclined outer margins of the side walls of the holder 69.

When a pair of transversely positioned box body blanks have been engaged in a tilted holder 69 the oscillating cross bar 56 acting on the respective slide bar 59 acts to move the outermost holder mechanism inwardly so that the roller 62 rolls upwardly

on the inclined runway 61, thereby actuating the toggle mechanisms 65 and 66 to cause the inclined holder to be rotated downwardly into a horizontal position as it advances inwardly to engage the body portion of the box over a box former or mandrel 77 which is formed with tapered side walls. The reduced outer end of the former 77 is recessed at 78 to receive a retaining nut 79 which serves to hold the former 77 in place on the outer reduced end 80 of a rotatable shaft 81. The former is keyed on the reduced portion 80 of the shaft 81 to permit the former to be rotated with said shaft. The enlarged end 15 of the former 77 is also recessed to fit over the outer end of a cylindrical bearing sleeve 82 in which the shaft 81 is journaled. The bearing sleeve 82 is provided with an apertured flange 83 which is rigidly secured to the machine framework by bolts 84 or other suitable means. The former 77 is provided with a peripheral groove 85, each of the four sides of which has a box slide or guide bar 86 slidably mounted therein, with the ends 20 of each guide bar chamfered and with the outer wall inclined at an angle greater than the angle of inclination of the side walls of the former 77. Each of the guide bars 86 is provided with a pair of recesses 87 through each of which a retaining bolt 88 projects, with the threaded end of the bolt engaged in the body of the former 77. Engaged around each of the retaining bolts 88 is a coiled spring 89 which is positioned below the head of the bolt so that said spring acts to resiliently hold said guide bar seated within the groove of the former 77. The former 77 is provided with four longitudinal 25 passages in each of which a box slide release pin 90 is slidably mounted. Each of the release pins 90 has one end chamfered at 91 and is furthermore provided with a chamfered notch 92 intermediate the ends thereof (Figure 9) and with a side notch 93 between the notch 92 and the outer end of the pin. The notches 92 are provided to register with the guide bars 86 when the pins are pushed inwardly to permit said guide bars to be pulled inwardly by the 30 springs 89 so that the sides of the box 76 may lie flat against the sides of the former 77.

The former 77 is also provided with a plurality of longitudinal drillings or passages substantially on the diagonal lines of the former, and each of said drillings has slidably mounted therein a box ejecting pin 94 having a portion 95 thereof (Figure 11) of reduced diameter around which a coil spring is engaged to normally hold the ejecting pins 94 projected. Both the slide pins 90 and the box ejecting pins 94 are adapted to be pushed inwardly by the holder 69 and the box bottom 75 contained therein with the inward movement of a holder. The

spring impelled ejecting pins 94 automatically move outwardly when the holder 69 moves away from the former 77 so that a box on the former is adapted to be automatically released, as hereinafter more fully 70 described.

The former 77 near the inner end thereof is provided with a second peripheral groove in which a split anvil hoop or rim 96 is seated, with the split ends spaced a slight distance apart and held in position by means of retaining screws 97 or other suitable means. The anvil hoop 96 is provided with a peripheral groove 98 which is curved to permit bending over or crimping of the ends 80 of wire staples used in finishing the box. Each former is provided with a hoop strip gripping or clamping mechanism comprising a stationary hoop holder or clamp 99, the body or stem of which is rigidly secured by screws or other suitable means to the inner face of the former 77 and is provided with a toothed or corrugated clamping head 100 projecting over one side of the former and slightly above the space afforded between the ends of the anvil hoop 96 (Figure 9). The former is provided with a radial recess at 101 in which a bearing plug 102 is slidably mounted and carries a ball bearing 103 which at a predetermined time is adapted to register with and seat in a detent 104 provided in the bearing sleeve 82 (Figure 9). The ball bearing 103 is adapted to be resiliently held in the detent 104 by means of a coiled spring 105 engaged around a stem 106 on the upper end of which a movable corrugated hoop clamp or catch 107 is secured, with said catch 107 slidably disposed in the space afforded between the separated ends of the anvil hoop 96. When the former 77 is rotated ball 103 passes out of the detent 104 and rides on the periphery of the sleeve 82, thereby compressing the spring 105 and acting to push the hoop catch 107 outwardly toward the stationary hoop clamp 100 to clamp or lock one end of a hoop strip or band 108 to the former 77 preparatory to winding said hoop strip around the former from the position shown in Figure 22 into the position shown in Figure 23, this, of course, being done before the holder 69 moves into coacting engagement with the former 77 to position a box body in place.

A hoop strip feeding mechanism is provided on the machine for alternately feeding hoop strips of predetermined length from opposite sides of the machine in alternating relation to the two box forming mechanisms. Mounted on the shaft 50 below the table 4 is a large gear 109 which meshes with a horizontal feed rack 110 (Figure 2) secured on the under face of a horizontal bar of a U-shaped frame or yoke 111 positioned transversely of the machine beneath the table 4, with the side members of said frame project-

- ing outwardly on each side of the machine framework. Mounted on each of the arms of the rack frame 111 is an inwardly directed finger 112 having a chamfered end provided for the purpose of coacting with the chamfered ends 91 of the release pins 90 to individually slide said pins from their innermost positions to their outwardly projecting positions after a box forming operation.
- 5 The rack frame 111 is slidable between guide members 113 provided on the bottom of the table 4 (Figure 14). Secured on each side of the machine frame 2 is a bracket 114 on the front face of which 15 a hoop strip guide plate or track 115 is mounted. Formed longitudinally along one margin of the track 115 is a flange 116 which terminates at its outer end in a boss or shoe 117 having a beveled or chamfered surface 20 at its inner end. The track 115 is also provided with a longitudinal slot 119 in which a guide arm 120 carried on the rack frame 111 is adapted to slide. One end of the guide arm 120 is directed upwardly to 25 engage in the slot 119 and has the upper surface knurled or corrugated at 121 (Figure 20) to afford a lower catch or clamp to coact with a corrugated or knurled hoop strip gripping finger 122 which is integrally formed at one end of a hoop strip pawl or 30 catch 123 which is pivotally mounted on an arm of the rack frame 111. Mounted at right angles on the free end of the catch 123 is a hoop catch roller pin 124 on the outer end of which a hoop catch roller 125 is rotatably mounted. The roller 125 is adapted to track on the flange 116 of the hoop strip guide track and ride over the shoe 117 to elevate the catch 123 from the gripping position shown in Figure 20 into the released position shown in dotted lines in Figure 21 to permit a hoop strip 108 to be slidably engaged over the track 115 until the inner end of the hoop strip comes into contact with a hoop strip holder or stop pawl 123 which is pivotally mounted intermediate its ends on the front face of the machine, as indicated in Figure 20. With the inward movement of the catch 123 by the rack frame 111 the roller 125 is adapted to roll off of the shoe 117 to 45 permit the catch to be lowered so that the catch finger 122 will grip the hoop strip between the finger 122 and the lower catch finger 121 to cause the hoop strip to be fed inwardly or advanced beneath a guide finger 127 which is also pivoted on the front face of the machine frame 2. The advance end of the hoop strip 108 after passing beneath the guide finger 127 is thus guided 50 over one face of the former anvil hoop 96 into the position shown in Figure 22, with the advance end of the hoop strip 108 engaged between the hoop clamp 100 and the hoop catch 107 at which time the ball bearing 103 is in register with the detent 104

(Figure 9) so that the spring 105 acts to hold the hoop catch 107 in its released or lowered position.

At the time that the box body holder 69 advances from an outer filling position inwardly toward its respective former 77 the slide bar 59 supporting the holder is moved inwardly by the reciprocating cross bar 56. Mounted on the upper face of the inner end of the slide bar 59 is an upwardly tapered cam block 128 which is provided with a central longitudinal groove or slot in which a sliding cam 129 is slidably positioned. The sliding cam 129 is provided with a longitudinal slot 130 (Figure 9) through which a pin 131 carried by the cam block 128 projects. The sliding cam 129 is adapted to be moved longitudinally back and forth through the cam block 128 during the operation of the machine. The movement of the sliding cam is accomplished by means of a guide roller 132 which is rotatably supported in the notched or forked end of a downwardly directed arm or post 133 secured by any suitable means to the middle portion of the lower member of a roller lift yoke or frame 134. The roller lift yoke 134 is slidably engaged in a peripheral groove 135 provided in the bearing sleeve 82 (Figure 9). Mounted on the top member of the roller lift yoke 134 is a bracket arm or push rod 136 on the upper front face of which a plunger 137 is secured. The lower end of the plunger is notched or bifurcated to rotatably support a presser wheel or presser roll 138 in position to resiliently press or roll over the hoop strip 108 of a box during the making of the box so that the hoop strip is tightly bound around the upper portion of the box. The plunger 137 is slidably mounted in a notch 139, provided for the purpose, in the lower end of a stapler case 140 which is secured on the front face of the machine frame 2 by means of a bracket 141. As shown in Figure 14 the plunger 137 is provided with a stem which projects into the recess 139 and has a coiled spring 142 engaged thereon for normally holding the presser roll 138 in a lowered position when the lift roll 132 is off of its respective sliding cam 129.

The rotating mechanisms for rotating the former 77 will now be described and attention is directed to Figures 7 and 8 of the drawings. One of the former shafts 81 projects rearwardly through a bearing sleeve or collar 143 supported on the machine framework 2 and has the outer end journaled in a bearing 144 secured by means of a bracket 145 to the machine framework. Keyed or otherwise secured on the shaft 81 adjacent the bearing sleeve 143 is a large driving gear 146 adapted to rotate one of the formers 77. Meshing with the driving gear 146 is a second driving gear 147 on one side of which a ratchet 148

is secured. The ratchet 148 is keyed to a second shaft 81 which is also journaled in a bearing sleeve 143 and in a bearing 144. Pivotally mounted on the second shaft 81 adjacent the ratchet 148 is a crank 149 having a crank pin 150 on which a connector 151 is pivotally mounted. Supported on one side of the crank 149 is a driving pawl 152 which coacts with the toothed periphery of the ratchet 148. The ratchet 148 is provided with four teeth spaced ninety degrees apart so that each of the formers is adapted to be rotated through ninety degrees each time the driving pawl 152 actuates the ratchet 148. Connected to the connector 151 is the lower end of a connecting rod 153 the upper end of which is pivotally connected to a crank 154 forming a part of the main crank shaft 20 (Figure 1). With each quarter rotation of a former to which a hoop strip 108 is clamped, as shown in Figure 22, the hoop strip is wound around one side of the former so that with a complete rotation of the former the hoop strip 108 is wound around the four sides of the former, with a portion of the fourth side overlapping the advanced portion of the strip which is held clamped by means of the clamping head 100. This condition is illustrated in Figure 23, at which time a box body holder 69 is advanced inwardly toward its former to slidably project the box sides 76 over the former and over the spring compressed projecting guide bars 86 which serve to deflect or guide said box sides 76 outwardly so that the advanced ends of said box sides will project over and be disposed to the outside of the first loop of the hoop 108, as illustrated in Figure 24. The former is again rotated a quarter of a revolution at a time so that the hoop strip is wound around the former a second time to the outside of the box sides 76 to bind the upper margins of said box sides by means of said hoop. During this second revolution of a former at each quarter revolution a stapling mechanism is automatically brought into operation to staple each side of the box between two turns or laps of the hoop 108. The stapling mechanism may be of any desired standard construction and is adapted to be operated from the main crank shaft 20 on the forward end of which a crank arm 155 is mounted. Rotatably mounted on the outer end of the crank arm 155 is a slide block 156 which is positioned to reciprocally slide in the head of a cross head member 157. The cross head member is provided with a T-head 158 which is slidable in a T-slot 159 provided in a guide block 160 secured on the upper portion of the front face of the machine framework 2. Formed on the lower end of the cross head 157 is a main stapler operating plate 161 to which a pair of stapler heads 162 are adjustably mounted. Two sets of

stapling mechanisms are provided on the front of the machine, both identically constructed, one of which will be described. Secured to the stapler head 162 are a pair of stapler driving plates 163 which slidably project into the stapler case 140 and coact with stapler formers 164 to form wire staples formed from wire which is automatically fed into the stapling mechanism. Attached to each end of the main stapler operating plate 161 is a bracket 165 on the end of which is mounted a slotted wire feed rod or bar 166, the lower end of which is connected to operate a wire feed mechanism 167 mounted adjacent the lower end of the stapler case 140. As a box is being completed and the hoop 108 is wound around each side 76 of a box, as shown in Figure 25, the wire feed mechanism 167 is operated to feed a predetermined length of wire to the stapling mechanism which is automatically operated with each quarter rotation of a former so that staples 168 are driven through the hoop strip 108 and the respective box sides 76 to tightly secure the hoop in position around the upper margin of the box to complete the same.

The operation is as follows:

Having described in detail the various parts of the improved box making machine a brief description of the operation will now be given. The machine is adapted to be driven from any suitable source of power by means of a belt engaged over the loose pulley 8. When an operator steps on the foot pedal 17 the lever 13 actuates the connecting bar 12 to cause the bell crank 10 to move the clutch 9 into gripping relation with the loose pulley 8 so that a drive is transmitted from the driving pulley to the shaft 6 and the driving pinion 18. The pinion 18 being in mesh with the large gear 19 acts to rotate the main crank shaft 20, thereby causing operation of a plurality of different mechanisms through the connecting rods 23 and 153 and by means of the cross head 157.

The reciprocating connecting rod 23 is adapted to intermittently rotate the timer gear ratchet 28 by means of the pawl 25 to rotate the shaft 26 and the toothed cam 42 (Figure 5) to alternately cause operation of the mutilated gears 37 and 46 which in turn operate the gears 36 and 49, respectively, and the train of idler gears 31-34 to cause rotation of the shaft 50 and the beveled gear 53 and the gear 109, both of which are mounted on said shaft.

The beveled gear 53 operates the beveled gear 54 and thereby causes a reciprocating or swinging movement to be imparted to the cross bar 56, which being connected to the slide bars 59 causes the box holder mechanisms 69 to be alternately moved inwardly and outwardly toward and away from the respective box formers 77.

As the box holders are being operated the

gear 109 simultaneously acting on the rack 110 reciprocates the slide frame 111 to alternately cause the hoop strip feed mechanisms (Figures 18 to 21) to be operated. When one of the hoop strip feed tracks 115 is in its outermost position, as illustrated in Figures 18 and 21, the hoop strip catch 123 is in an elevated or released position permitting an operator to slide a hoop strip 108 of a predetermined length over the track 115 until the inner end of said hoop strip contacts the stop or pivoted pawl 126. When the slide frame 111 moves one side of said frame inwardly the roller 125 rolls off of the shoe 117, thereby permitting the catch 123 to be lowered into the position shown in Figure 20, so that the catch finger 122 will act to grip the hoop strip 108 at a predetermined distance from its end between the finger 122 and the lower gripping finger 121. The hoop strip is now advanced inwardly to first tip the pawl 126 upwardly and then pass beneath the pivoted hoop strip guide 127 substantially half way across one side of a former 77 into the position shown in Figure 22, with the advanced end of the hoop strip resting on the grooved anvil hoop 96 with the tip end of the hoop strip engaged beneath the corrugated clamping head 100 and above the hoop strip catch 107 which at this period in the operation is in its lowered position due to the fact that the ball bearing 103 is seated in the detent 104, permitting the spring 105 to hold the catch 107 in its released position.

At this point in the operation the connecting rod 153 causes the pawl 152 to actuate the ratchet 148, thereby causing the former control gears 146 and 147 to be rotated one quarter of a revolution each time the pawl 152 actuates the ratchet 148 (Figure 7). At the time that the revolution of a former is started the ball bearing 103 moves out of the detent 104 and rides on the periphery of the bearing sleeve 82 (Figure 9) so that the gripping catch 107 is moved outwardly toward the gripping clamp 100 to lock or tightly clamp the advanced end of the hoop strip 108 to the former. Upon a complete rotation of a former the hoop strip is wound once around the former and over the top of the clamp 100, as shown in Figure 23.

At this period in the operation the machine is so arranged and timed that the reciprocating cross bar 56 acts to move a box body holder from its outer loading position inwardly toward its respective former. When the holder 69 is in its outer position the roller 62 is permitted to be positioned on the outer depressed end 61 of the guide rail 60 (Figure 14), thereby permitting the control spring 74 to actuate the toggle mechanisms 65-66 to swing the holder 69 into an inclined position to permit an operator to place a pair of transversely creased body blank forms in position, with said forms crossed in overlapping right an-

gle relation to one another with the end portions 76 bent along the respective creases to form box sides 76 while the middle portions of the overlapped blanks form the box bottom 75. As the holder 69 is advanced inwardly the roller 62 rolls upwardly on the inclined portion 61 onto the track 60, thereby causing the toggle mechanism 65-66 to be operated to swing the loaded holder 69 from an inclined loading position into a horizontal position in alignment with its respective former 77. As the loaded holder is brought into coacting relation with its respective former 77 the side walls 76 of the box within the holder are moved into engagement with the slanting side walls of the former and slide over said former walls until the spring impelled guide bars 86 are reached causing the outer inclined walls of said bars 86 to deflect or bend the box walls 76 outwardly so that the advanced ends of the side walls 76 will ride over the first loop of the partially formed hoop 108 into the position shown in Figure 24. As the box body is advanced by a holder 69 onto a former 77 the bottom of the box 76 is first brought into contact with the outer projecting ends of the slidable release pins 90, thereby causing the four pins 90 to be pushed inwardly until the chamfered notches 92 are brought into register with the respective bars 86 permitting the control springs 89 (Figure 13) to pull the respective bars 86 inwardly, thereby permitting the box sides 76 to lie flat against the sides of the former 77 and against the partially wound hoop strip 108. With the continued advance of the box bottom 75 toward the former 77 the box bottom also serves to push the spring impelled box ejecting pins 94 inwardly, thereby compressing the control springs of said pins 94 as long as the holder is in coacting relation with its former 77.

The respective former control gear 146 or 147 now again acts to rotate the respective former through ninety degrees to cause the hoop strip 108 to be wound around the outer face of one of the box sides 76. When this is done the cross head 157 is moved downwardly, thereby actuating the wire feed bar 166 to cause a predetermined length of wire 115 to be fed by the wire feed mechanism 167 into the stapler case 140. The cross head plate 161 simultaneously acts to operate the stapler head 162 and the stapler driving plates 163 which coact with the stapler formers 164 to automatically cut the advanced piece of wire and form staplers therefrom, which staples are automatically driven through the two laps of the hoop strip and through the respective outer margin of the box sides 76, thereby causing the staples 168 to clamp the hoop to one side of the box. The former 77 is successively rotated through quarter revolutions at properly spaced intervals of time so that the hoop strip is engaged 120 125 130 135 140 145 150 155 160 165 170 175 180 185 190 195 to the outside of the respective box sides and is stapled thereto to form a completed box, as shown in Figures 25 and 26.

At this stage in the operation the cross bar 56 acting on the advanced holder 69 retracts said holder causing the release roller 132 (Figure 14) to ride over the sliding cam 129, thereby sliding the yoke 134 upwardly to release the spring controlled presser roller 138 from rolling contact with the hoop 108 of the completed box. As soon as the slide cam 129 passes the roller 132 the frame 134 and the roller 132 are permitted to drop off of the straight edge of the cam 129, thereby permitting the presser roller 138 to again be lowered. As the holder 69 is moved away from the former and the completed box thereon, the spring pressed ejecting pins 94 automatically act to push the completed box outwardly off 20 of the former so that as soon as the holder is moved out of the way an operator may remove the partially ejected box from the former on which it was made.

The duplex machine is so arranged that 25 when one of the holders 69 moves outwardly toward a loading position the other holder is in its inner position coacting with its respective former to permit a box to be formed, as hereinbefore described. The machine is thus 30 capable of forming boxes on the two formers 77 with an attendant placing the creased body blanks in the holders when in their outer inclined positions. The attendant also feeds the hoop strips onto the tracks 115 and 35 catches or removes the completed boxes as they are ejected from the respective formers by the spring impelled ejecting pins 94.

At the time that a holder is retracted from coaction with its former the spring impelled 40 box release pins 94 are, of course, projected outwardly, but the box slide release pins 90 which were projected inwardly by the inward movement of the holder remain in position with their chamfered ends projecting from 45 the rear of the former until the holder is retracted and the box removed so that it becomes necessary to project said pins 90 outwardly through the front end of the former before the next inward feeding movement 50 of a holder. During the time that a former is rotated through one complete revolution to permit the first lap of a hoop strip to be engaged around a former the reciprocating frame 111 is reciprocated, thereby causing 55 the chamfered finger 112 to be brought into contact with the chamfered end face 91 of the pins 90, thereby causing said pins to slide outwardly moving the notches 92 out of register with the respective spring impelled 60 former bars 86 so that said bars are again moved outwardly into a projecting position from the respective sides of the former in a position ready to guide the box sides 76 of the next box body advanced by a holder 69.

65 The boxes are adapted to be formed out of

thin sheets of wood or other suitable material and out of a hoop constructed of flexible wooden strips or other material permitting the use of wire staples to hold the hoop secured to the upper peripheral margin of the 70 box.

We are aware that many changes may be made, and numerous details of construction may be varied through a wide range without departing from the principles of this invention, and we therefore do not purpose limiting the patent granted hereon, otherwise than necessitated by the prior art.

We claim as our invention:

1. A box making machine comprising a 80 framework, a crank shaft journaled thereon, means for driving the crank shaft, a rotatable box former supported on said framework, means operated by the crank shaft for intermittently rotating the former, a slideable pivotally mounted box blank holder mounted in an inclined position on the framework, means operated from the crank shaft for reciprocating said holder and pivotally swinging the same into a horizontal position to cause the same to coact with said former, a hoop strip feed mechanism operated by said last mentioned means to feed a hoop strip to the former, means for removably clamping the hoop strip to the former to permit said hoop strip to be wound once around the former prior to the advance of a box body over the former by said holder to permit a second lap of the hoop strip to be wound around the side walls of said box, a stapling mechanism operated at predetermined times from said crank shaft to cause staples to rivet the laps of the hoop strip to the outer margins of the side walls forming the box, and means for releasing the formed box upon withdrawal of the 90 holder.

2. A box making machine comprising a framework, a crank shaft journaled thereon, a driving means for operating the same, a box former rotatably mounted on the framework, a pivoted box holder slidably mounted in an inclined position on the framework, means for swinging the holder into a horizontal position for coaction with the former, a hoop strip feed mechanism coacting with the former, a riveting device operated by the crank shaft and adapted to rivet a hoop to the body of a box positioned on the former by said holder, means connected with the crank shaft for rotating the former, and mechanisms connected to be operated by the crank shaft adapted to operate the holder and said hoop strip feed mechanism.

3. A box making machine comprising a 125 framework, a crank shaft mounted thereon, a driving means for operating the crank shaft, a box former on the framework connected to be operated from the crank shaft, a pivotally supported box body holder connected to be operated from the crank shaft and adapted to 130

be tilted from an inclined loading position into a horizontal position for advancing a pair of crossed body blanks onto said former, means for automatically winding a hoop strip around the former and around a box body when positioned on the former, and a stapling mechanism operated from the crank shaft adapted to staple the hoop strip to the box body to form a completed box.

4. A box making machine comprising a framework, a main shaft journaled thereon, means for operating the main shaft, and a rotatable box former; a pivoted slidably supported box body blank holder mounted in an inclined loading position and adapted to be tilted into a position of alignment for coaction with said box former, a hoop strip feed mechanism, and a stapling mechanism all connected to be operated in timed relation by said shaft to cause a hoop bound box to be formed and stapled.

5. A box making machine comprising a framework, a shaft journaled thereon, a driving means for operating the same, a box former connected to be operated from said shaft, a hoop strip feed device connected to be operated from said shaft to advance a hoop strip to the former, releasable clamping mechanisms on the former for holding the hoop strip attached thereto as the hoop strip is wound around the former, a reciprocating pivotally supported box body blank holder mounted in an inclined position on the framework, means connected with said shaft to operate the box body blank holder to cause the same to swing into alignment with said former to coact with the former at a predetermined time to permit the hoop strip to be wound around the outer margins of the side

walls of the box body, a stapling mechanism connected to be operated from said shaft to staple the hoop strip to the margin of the box body to form a completed box, and ejecting means on the former for releasing the finished box with the retraction of the box body blank holder.

6. A box making machine comprising a framework, a rotatable box former mounted thereon, a pivoted box body blank holder normally inclined and adapted to be swung into a horizontal position for coaction with said former, a sliding support therefor, a hoop strip feed mechanism for coaction with the former, a stapling mechanism for coaction with said former, a crank shaft journaled on said framework, means for operating the crank shaft, and a plurality of mechanisms operated from the crank shaft to automatically actuate said former, said reciprocating holder, said hoop strip feed mechanism, and said stapling mechanism in predetermined order to cause a box having a stapled hoop to be formed.

7. A box making machine comprising a framework, a former rotatably mounted

thereon, means for winding a hoop strip around the former, a reciprocating holder for applying box body blanks to the former in engagement with the partially wound hoop strip in time to permit the second lap of the hoop strip to be engaged around the side walls of the box body, a toggle mechanism for swinging the holder into an inclined loading position out of alignment with said former, a stapling mechanism adapted to automatically secure the hoop by means of staples to the margin of the box body, and slideable spring controlled pins carried by the former adapted to release the box from the former when the box body blank holder is retracted.

8. A box making machine comprising a framework, a crank shaft supported thereon, a driving means for the crank shaft, a former rotatably mounted on the framework and operable from the crank shaft, a hoop strip feed mechanism connected to be operated from the crank shaft to supply a hoop strip to the former, clamping means on the former for engaging the hoop strip to cause the same to be wound around the former when the former is rotated, a pivoted box body blank holder normally set in an inclined position and slidably mounted on the framework, a roller controlled toggle mechanism for swinging the holder into alignment with the former, means operated from the crank shaft for reciprocating the holder to cause a box body to be engaged on the former between the laps of said hoop strip, and a stapling mechanism connected with the crank shaft and operable thereby to cause wire staples to rivet the hoop strip to the outer margins of the side walls of a box body to form a hoop bound box.

9. A box making machine comprising a framework, a crank shaft journaled thereon, means for operating the crank shaft, a tapered rotatable former supported on the framework, means operated by the crank shaft for rotating the former, a pivotally supported box body blank holder on said framework adapted to be swung into an inclined position to permit loading of the same, means operated from said crank shaft for pivoting said holder into a horizontal position and advancing the same, to cause the holder to coact with the former to supply a box body to the former, a hoop strip feed mechanism connected to be operated from the crank shaft to cause a hoop strip to be wound around the inner periphery and the outer periphery of the top margin of the box body, a wire stapling mechanism connected to be operated from the crank shaft to rivet the hoop to the outer margin of the box body by means of wire staples, and a wire feed mechanism operated from said crank shaft to supply stapling wire to the stapling mechanism.

10. A box making machine comprising a framework, a tapered former rotatably

mounted thereon; means for intermittently rotating the same, means for feeding a hoop strip to the former to permit the hoop strip to be wound around the former, a box body blank holder supported in inclined position for loading, means for tilting the same from an inclined loading position and then moving the same into coacting relation with the former to cause a pair of crossed box body blanks to be applied onto the former in engagement with the hoop strip, a stapling mechanism coacting with the former, means for operating the same at predetermined times to cause the hoop strip to be stapled to the various sides of the box body as the same is rotated by said former, and ejecting pins on said former adapted to automatically release the formed box on the former when said holder is moved out of coacting relation with said former.

11. A box making machine comprising a framework, a tapered holder rotatably mounted thereon, means for operating the same, means for automatically supplying a hoop strip to the former, gripping means on the former for automatically securing the end of the hoop strip to the former to permit the hoop strip to be wound around the former as the former is rotated, a box body blank holder, means for operating the same to cause the holder to advance a pair of crossed box body blanks into engagement with the former, spring controlled bars carried by the former adapted to cause the box body blanks to be guided over a lap of the hoop strip, notched pins carried by the former adapted to be operated by the holder to permit the spring impelled bars on said holder to be moved inwardly to permit the sides of the box body to seat against the hoop strip wound around said former prior to the completion of the winding of said strip around the outer periphery of the box body, a stapling mechanism coacting with the former to cause the hoop strip to be stapled to the outer margins of the box body sides to form a completed box, a box ejecting mechanism on said former adapted to release said box when the holder is retracted, and means for sliding said notched pins into their normal positions to again project said bars after a box has been released.

12. A box making machine comprising a framework, a former rotatably mounted thereon, means for operating the former, a slideable support, means for reciprocating the same, a normally inclined box body blank holder pivoted on said support, toggle means controlling the pivotal movement of the holder to position the same in alignment with the former to deliver box body blanks thereto, mechanisms for feeding a box hoop strip to the former to permit the hoop strip to be wound around the margins of the box body blanks, stapling means for coaction with

the former to cause the hoop strip to be stapled to the outer margins of the box body blanks to form a completed box, and means for releasing the box from the former after a stapling operation.

13. In a box making machine of the class described the combination with a former, means for rotatably supporting the same, a hoop strip feed mechanism operated by the machine for feeding a hoop strip to the former, automatically acting gripping means on the former adapted to automatically grip the hoop strip to lock the same on the former, a body blank feed mechanism advanced by the machine to the former, spring controlled guide bars on the former for guiding the box body blanks onto the hoop strip, notched pins carried by the former adapted to be operated by the body blank feed mechanism to permit said bars to be retracted permitting the box body blanks to be brought into contact with the hoop strip prior to the completion of the winding of said hoop strip around said box body blanks, a stapling mechanism operated from the machine to automatically staple the hoop strip to the box body blanks to form a completed box, and spring impelled ejecting pins carried by the former adapted to be compressed by the box body blank feed mechanism when body blanks are fed to the former and further adapted to automatically release the formed box from the former when said box body blank feed mechanism is retracted.

14. In a box making machine of the class described the combination with a rotatable box former, means for intermittently rotating the same, a box body blank carrying mechanism adapted to apply crossed body blanks onto said former, means for operating said box body blank feed mechanism, a hoop strip feed mechanism operated from the machine adapted to supply a hoop strip to the former, locking means on the former for engaging the hoop strip to cause the same to be looped around the former a plurality of times on opposite sides of the box body blanks, a cam controlled presser roller mechanism coacting with the former for pressing the hoop strip as it is being wound, a wire stapling mechanism coacting with the former as it is rotated to cause the hoop strip to be stapled to the box body blanks to form a hoop bound box, means for automatically releasing said hoop strip locking means upon the completion of a box, a slideable cam movable with the blank carrying mechanism for releasing said presser roller mechanism, and ejecting means on the former for releasing the completed box when the box body blank feed mechanism is retracted and the locking means and the presser roller mechanism are released.

15. In a box making machine of the class described the combination with a rotatable

former, means for operating the same, a slidable bar, means for reciprocating said slidable bar, a box body blank holder pivotally supported on said bar, means for automatically swinging said holder into and out of horizontal position, said holder when in horizontal position adapted to be advanced to carry the box body blanks into coacting engagement with the former, a slidable cam on said reciprocating bar, a hoop strip feed mechanism operated by the means which operates the reciprocating bar and adapted to automatically feed a hoop strip to the former, gripping means on the former for engaging the hoop strip to permit the same to be wound around the former and around margins of the box body blanks, a presser roller mechanism adapted to be actuated by said slidable cam to press against the hoop strip as it is being wound around the former, a wire stapling mechanism positioned to coat with the former, and means for operating the same to cause the wound hoop strip to be stapled to the margins of the box body blanks to form a completed box.

16. In a box making machine of the class described the combination with a rotatable former of a reciprocating support, means for operating the same, a box body blank holder pivotally mounted on said support, means connected with the holder for tilting the same into a loading position and returning the same to normal position when the holder is advanced to coat with the former, means for feeding a hoop strip to the former to permit the hoop strip to be wound around margins of the box body blanks, and means for automatically securing the hoop strip to the margins of the box body blanks to form a completed box.

17. In a box making machine of the class described the combination with a rotatable former, means for intermittently rotating the same, a pivotally supported box body blank holder adapted to be tilted into an inclined position to permit loading, means for moving the holder into coacting aligned relation with the former, a hoop strip feed mechanism, means for operating the same to cause the hoop strip to be advanced into engagement with the former, gripping means on the former permitting the hoop strip to be wound on the box body blanks to form a binding hoop, and means for automatically securing the hoop to the box body blanks to form a completed box.

18. In a box making machine of the class described the combination with a rotatable former of a slidable bar, a presser roll coacting with the former, a slidable cam on said bar adapted to actuate the presser roll at predetermined times, means for operating said slidable bar, a blank holder pivotally supported on said bar, a spring controlled toggle mechanism for tilting the holder into

an inclined loading position, and means for actuating the spring controlled toggle mechanism to cause the holder to be swung into a horizontal position when loaded to cause box blanks to be advanced into coacting engagement with the former.

19. In a box making machine of the class described the combination with a rotatable former, of a hoop strip feed mechanism adapted to automatically advance a hoop strip into engagement with the former, a pivotally supported box blank holder normally positioned in an inclined loading position to permit box blanks to be seated therein, mechanisms for swinging the holder into a horizontal position and then advancing the same toward the former to permit the hoop strip to be wound around the box blanks, and a stapling mechanism adapted to automatically staple the hoop to the box blanks to form a completed box.

20. In a box making machine of the class described the combination with a rotatable former, means for operating the same, a feed mechanism for advancing a hoop strip into engagement with the former, a slidable bar, a cross arm for reciprocating the same, means for actuating the cross arm, a support on said slidable bar, a box blank holder pivotally mounted on said support, a spring controlled toggle mechanism on said support for swinging the holder into an inclined loading position, an inclined track, a roller mechanism connected with said toggle mechanism adapted to run on said track to cause the inclined box blank holder to be swung into a horizontal position as it is advanced toward the former to permit the hoop strip to be wound around the box blanks, a stapling mechanism, and means for automatically operating the same to cause the hoop strip to be stapled to the box blanks.

21. In a box making machine the combination with a rotatable former, of means for operating the same, a slidable support, means for reciprocating said support, a box blank holder pivotally mounted on said support, means for moving said holder from an inclined loading position into a horizontal position as the holder is advanced toward the former to engage the box blanks on the former, means for feeding a hoop strip to the former to permit said hoop strip to be wound around the former and around portions of the box blanks, a stapling mechanism for securing the hoop strip to said box blanks to form a completed box, and means on said former for automatically releasing the box when the holder is retracted.

22. In a box making machine the combination with a rotatable former, means for operating the same, a pivotally mounted holder adapted when in an inclined position to have a pair of box body blanks seated therein in crossed relation, means for swing-

ing the holder into alignment with the former and then advancing the holder into co-operating relation with the former to cause the box body blanks to be shaped to form the body portion of a box, a hoop strip feed mechanism, means for operating the same to cause the hoop strip to be fed to the former, gripping means on the former for holding the hoop strip attached thereto to permit the hoop strip to be engaged with the box body blanks, a presser roller engaging the hoop strip as it is fed to the former, means for controlling said presser roller, a stapling device, means for operating the same at predetermined times to cause the hoop strip to be stapled to the box body blanks to form a completed box, and ejecting means on the former for automatically discharging the formed box when the presser roller is released and said holder is retracted.

23. In a box making machine the combination with a rotatable former, means for operating the same, a slidable support, means for reciprocating the same, a holder pivotally mounted on said support adapted to carry a plurality of box body blanks in crossed relation, means on said support for moving the holder from a loading position into a position in alignment with said former to permit the box body blanks to be fed to the former, a hoop strip feed mechanism, means for actuating the same to feed a hoop strip to the former for engagement around the box body blanks, a presser roller mechanism coacting with the former to press the hoop strip as it is being engaged around the box body blanks, a slidable cam on said support for moving the presser roller mechanism out of operating position, means for rigidly securing the hoop strip to the box body blanks to form a completed box, and means for automatically discharging the completed box from the former when said holder is retracted into its loading position.

24. In a box making machine the combination with a former, of means for operating the same, a box body blank applying mechanism and a hoop strip feed mechanism adapted to supply box body blanks and a hoop strip to the former to be formed into a box, a mutilated gear mechanism for governing the operation of said box body blank applying mechanism and said hoop strip feed mechanism, a toothed cam operating said mutilated gear mechanism at predetermined times, eccentric means operating the said toothed cam, and driving means operating said eccentric means.

25. In a box making machine comprising a framework, a crank shaft supported thereon, driving means for the crank shaft, a clutch mechanism to set the driving means in operation, a former, pawl and ratchet means connected therewith, means for operating the pawl and ratchet means from the

crank shaft to cause intermittent rotation of the former, a mutilated gear mechanism, pawl and ratchet means for operating the same, eccentric means operated by the crank shaft for operating said last mentioned pawl and ratchet means, a gear shaft operated by said mutilated gear, a rack frame, a gear on said gear shaft for reciprocating said rack frame, a hoop strip feed mechanism on said rack frame for feeding a hoop strip to the former, gripping means on the former for engaging the hoop strip to cause the hoop strip to be wound around said former, presser means for guiding the hoop strip into position, a slidable support, means operated by the gear shaft for reciprocating said slidable support, a slidable cam mechanism on said support for governing the operation of said presser means, a box body blank holder pivotally mounted on said support, toggle means for operating said holder to swing the holder from an inclined loading position into a position in alignment with said former to permit the box body blanks to be fed to the former and engaged by said hoop strip as it is wound into position, a stapling mechanism coacting with the former, a wire feed device associated with the stapling mechanism, a cross head mechanism operated by the crank shaft adapted to operate both the stapling mechanism and said wire feed device to cause the hoop strip to be stapled to the box body blanks to form a completed box, means on said former for releasing the gripping means after a box has been formed, and ejecting means on said former adapted to automatically discharge the completed box when said holder is retracted toward its loading position.

26. The improvement in the art of making a basket which consists in forming a shell with a bottom and a surrounding side wall, providing a preformed hoop of a diameter greater than that of the bottom, then slipping the shell onto a tapered form and separating the upper end of the side wall from the form so as to step the upper edge of said side wall over the exposed edge of said hoop on the enlarged end of the form, then securing the upper end of the shell between said hoop and an outer band and then removing the resultant structure from the form.

27. In a basket making machine the combination of a tapered form adapted to have a basket shell of assembled panels with ends thereof unconnected at one end of the shell applied endwise thereon, a hoop seat at the larger end of the form, a member between the ends of the form and projecting outwardly therefrom so as to engage the interior of the basket shell and deflect the unconnected ends of the panels away from the form and over the hoop on said seat, and mechanism for securing a plurality of bands around the

shell on said form and for securing the hoop on said seat to the end of the shell.

28. The improvement in the art of making a basket which consists in forming a shell with a bottom and a surrounding side wall, providing a preformed hoop of a diameter greater than that of the bottom, then slipping the shell onto a tapered form and separating the upper end of the side wall from the form to admit the said hoop therebetween, then securing the upper end of the shell between said hoop and an outer band and then removing the resultant structure from the form.

29. In a basket making machine the combination of a tapered form adapted to have a basket shell of assembled panels with ends thereof unconnected at one end of the shell applied endwise thereon, a hoop seat at the larger end of the form, and means adjacent and adjustable relatively to the periphery of the form to engage the interior of the shell and guide the unconnected ends of the panels over the hoop on the aforesaid hoop seat.

30. In a basket making machine the combination of a tapered form adapted to have a basket shell of assembled panels with ends thereof unconnected at one end of the shell applied endwise thereon, a hoop seat at the larger end of the form, said form having an annular bulge at a distance from the hoop seat and extending outwardly from the form for spreading the end of the shell so that the unconnected ends of the panels engage over the hoop on the hoop seat.

35. 31. In a machine of the class described, the combination of a form for expanding an annular shell into a tapered form, means for holding a hoop in position so that the enlarged end of the tapered shell overlaps the hoop, an expansible deflecting means on the form for engaging and guiding the end of the shell over the hoop, and mechanism for fastening the enlarged end of the shell to the hoop.

45. 32. In a machine of the class described, the combination of a form for expanding an annular shell into a tapered form, means for supporting a hoop on the enlarged end of the form, radially shiftable members on the form and adjoining said means for temporarily expanding the enlarged end of the shell to guide said end onto the hoop, and mechanism for securing the expanded end of the shell to said hoop.

55. 33. In a machine of the class described, the combination of a form for expanding an annular shell into a tapered form, means for supporting a hoop at the enlarged end of the form, a plurality of deflectors arranged around the form, means for simultaneously adjusting the deflectors to guide the annular shell over the hoop and to release the shell so that the latter contracts against the hoop, and mechanism for fastening the annular shell to the hoop.

34. In a machine of the class described, the combination of a form for expanding an annular shell into a tapered form, a pusher adapted to engage the annular shell and slip the latter on the form, means for supporting a hoop at the enlarged end of the form, an adjustable deflector around the form cooperating with the pusher to temporarily enlarge the expanded shell as the latter is applied around the hoop, and means for securing the end of the annular shell to the hoop.

35. In a machine of the class described, the combination of a form for expanding an annular shell into a tapered form, a support for holding the annular shell adjacent the end of the form, a pusher for transferring the annular shell from the support onto the form, means for supporting a hoop at the enlarged end of the form, radially expansible means on the form cooperating with the pusher to temporarily enlarge the expanded shell so that the latter engages over the hoop, and mechanism for securing the annular shell to the hoop.

36. In a machine of the class described, the combination of a form for expanding an annular shell into a tapered form, means for advancing the form in a step by step manner, a support adjacent the smaller end of the form for holding a shell in position to be applied on the form, a pusher for transferring the shell from the support onto the form, means for holding a hoop adjacent the larger end of the form, expansible deflectors on the form cooperating in timed relationship with the pusher to internally engage the shell and guide the latter over the hoop and release the shell thereafter so that the shell contracts against the hoop, and stapling mechanism cooperating with the form to secure external hoops around the tapered shell on the form and to secure the aforesaid internal hoop to the shell.

In testimony whereof we have hereunto subscribed our names.

LOUIS F. SCHULGEN.
GEORGE F. SCHULGEN.
